METHOD OF PRESSING ZIPPER TAPES

William T. Carson, Haddonfield, N. J.

Application October 22, 1949, Serial No. 122,955

3 Claims. (Cl. 28—74)

1

This invention relates generally to the manufacture of zipper tape and more particularly to improvements in apparatus for drying beaded zipper tapes after the same have been dyed their requisite colors.

In the manufacture of zipper tapes prior to the present invention it has been the customary practice to initially dye and dry-press the flat woven tape fabric preliminarily to securing to one longitudinal edge thereof the top and bottom cords which form the bead to which the zipper elements are subsequently clinched. Such practice has been followed because no provision has been made heretofore to permit pressing of the beaded tape without crushing the bead into such flattened shape as to make it difficult, if not impossible, to subsequently secure the zipper elements thereto.

Also, the prior conventional practice of initially preparing the flat woven tape and then securing thereto the zipper-retaining bead necessarily required separate dyeing of the tape and its bead, and inasmuch as the tape and the bead-forming cords are usually supplied by different sources of manufacture or in different lots, it is frequently the case that the manufacture of the beaded zipper tape finds that for a tape fabric of a given color there is on hand an insufficient or excessive supply of the same color cord, so that upon completion of a beaded tape of a certain color, there remains a surplus stock of tape or cord of a color which is not immediately usable and which must be stored away for an indefinite period against the uncertain eventuality that one or the other may be ultimately usable.

Having in mind the foregoing, it is among the objects of the present invention to provide an apparatus which is capable of pressing beaded zipper tapes without crushing the zipper-retaining bead edge thereof, thereby making possible the assembly of tape and bead-forming cords preliminarily to dyeing of the finished beaded tape to any desired color. As a consequence, the apparatus of the present invention makes possible the utilization of tape fabrics and cords supplied in natural color and the dyeing of the completely fabricated beaded zipper tape to insure exact color matching of the tape, its beaded edge and the binding yarn employed to secure the bead-forming cords to the tape. Further, the present invention also makes it practicable to re-dye to any desired color previously finished beaded zipper tapes. Inasmuch as the present invention makes available beaded zipper tape of

2

any desired uniform color throughout, it is apparent that the manufacturer whose business it is to mount the zipper elements thereon is enabled to more economically meet his own requirements and those of his customers.

Other objects and advantages of the present invention will appear more fully hereinafter, it being understood that the present invention consists substantially in the combination, construction, location and relative arrangement of parts, as well as in the method of manufacturing zipper tapes, all as described in detail hereinafter, as shown in the accompanying drawings, and as finally pointed out in the appended claims.

15. In the accompanying drawings,

Figure 1 is a perspective view of the tape drying apparatus as constructed in accordance with the principles of the present invention;

Figure 2 is a partial vertical sectional view of 20 a pair of the heated drying rolls of the apparatus; and

Figure 3 is an enlarged perspective view of another set of rolls forming part of the present apparatus.

25. Referring now more particularly to the drawings, it will be observed that the present invention relates to the manufacture of beaded zipper tapes and more particularly to the pressing and drying of such tapes after the same have been dyed, the zipper tape treated by the apparatus of the present invention being of the conventional type formed of a relatively narrow flat web 10 of any suitable material, preferably woven cloth, having applied to one longitudinal edge 30 thereof top and bottom bead-forming cords 11—11 suitably secured to the top body by a binding yarn 12.

The cords 11—11 so secured to the edge of the flat tape 10 provide a longitudinally extending 35 bead to which the zipper elements (not shown) are adapted to be subsequently clinched. In accordance with the principles of the present invention, the tape body 10, the bead-forming cords 11—11 and the binding yarns 12 may all be formed of material in their natural color, the beaded zipper tape so formed being thereafter dyed to any desired color by any suitable dyeing process.

40. As shown in Figure 1, the apparatus of the present invention generally comprises a suitably journalled main supply roll 13 upon which are wound a plurality of separate rolls 14—14 of the beaded zipper tapes previously dyed to any desired colors, these rolls being arranged in suitably spaced relation along the supply roll 13.

Arranged immediately in advance of the tape supply roll is a suitable standard 15 provided at its upper edge with a horizontally extending guide bar 16 fitted with longitudinally spaced guide pins 17 to insure parallel travel of the several tapes over the bar and into and through a bath 18 of a suitable sizing liquid, e. g. a starch solution or the like, such bath being contained in a trough-shaped vessel 19 suitably provided in the bottom thereof with a revoluble guide roll 19a.

Disposed above the sizing vessel 19 are a pair of suitably journalled squeegee rolls 20—21 between which the tapes travel and which operate upon the tapes to squeeze therefrom the excess sizing liquid, the several tapes being thereafter drawn under and over a set of relatively fixed tension bars or rods 22, 23 and 24 disposed just in advance of a series of internally heated rotary drying drums 25.

These drying drums are respectively provided at corresponding ends thereof with intermeshing gears 26 and are so adapted to be rotated in unison by a single prime mover, such as an electric motor 27, suitably belted or otherwise drive-connected to any one of the drums. Each of the drums is internally heated, in accordance with conventional practice, as, for example, by gas burners which project axially into the interior of each drum in the form of suitably perforated gas burner pipes 28, the outer ends of which are connected, as at 29, to a common gas-supplying manifold 30.

The tapes moistened with sizing liquid passes through and between successive pairs of the drying drums 25 operating in the directions indicated by the arrows and finally emerge completely dry from the last drum in the series for delivery to and between a pair of cooperating slack take-up rolls 31 and 32 of which the lower roll 31 is adapted to be driven by a motor 33. The upper roll 32 is suitably mounted to freely float upon the driven roll 31 and is of a weight sufficient to press the intervening tapes against the drive roll and so insure the requisite longitudinal traverse of the several tapes through the rolls 31 and 32 as it is fed thereto from the final drying drum.

Figure 2 illustrates the preferred construction of the drying drums 25, while Figure 3 shows the preferred construction of all of the solid rolls, such as the squeegee rolls 20—21 and the slack take-up rolls 31—32.

It will be noted that the drying drums 25 are each provided with correspondingly spaced circumferentially extending grooves 34 in the tape traversing peripheral surfaces thereof, these grooves 34 being each of a depth and shape to snugly accommodate therein the bead-forming cord secured to one face of the woven tape 10. Inasmuch as the grooves 34 are correspondingly spaced lengthwise of the drums, the registering grooves of each adjoining pair of the drums provides a passage 35 therebetween for shaping the beaded edge of the tape as it passes through and between said pair of drying rolls. These passages are shown most clearly in Figure 2, wherein they are each designated by the reference numeral 35, it being noted that the passages 35 are spaced apart lengthwise of the drying rolls a distance sufficient to permit each pair of the latter to embrace therebetween and press the flat body portion of the beaded zipper tape.

In a similar manner, the squeegee rolls 20—21 and the slack take-up rolls 31—32 are each pro-

vided with longitudinally spaced circumferentially extending grooves 36, the spacing of these grooves lengthwise of their respective rolls being in correspondence with the spacing of the grooves 34 of the drying rolls. In addition, the guide roll 19a in the sizing vessel 19, as well as the tension bars 22, 23 and 24 are each similarly provided with circumferentially extending grooves longitudinally spaced in accordance with the spacing of the grooves in the drying drums and in the squeegee and slack take-up rolls.

It will be apparent that the grooves in the several members of the apparatus over and through which the several tapes pass not only prevent crushing of the beaded edges of the zipper tape during the process of pressing the same, but also serve to maintain the tapes in parallel relation as they traverse the apparatus. In addition, the passages 35 formed between adjoining pairs of the circumferentially grooved drying drums serve to mold and shape the sized corded edge of the tape into the form of a stiffened bead of substantially uniform cross-section through its entire length. As the pressed tapes emerge from between the final slack take-up rolls 31—32 they may be suitably rolled upon spools in requisite lengths for storage and shipment, the tapes in their final form being of uniform color throughout all of their component parts with their beaded edges in requisite condition and uniform cross-sectional shape for subsequent clinching thereto of the zipper elements.

It will be understood, of course, that the several elements of the apparatus of the present invention may be relatively arranged other than as shown. For example, the drying drums, the total number of which may be varied as desired, may be arranged in a horizontal rather than in the vertical relation shown, and it will accordingly be understood that the apparatus of the present invention is susceptible of various changes and modifications which may be made from time to time without departing from the real spirit and general principles of the invention, the scope of which is expressed in the appended claims.

What is claimed as new and useful is:

1. A method of manufacturing beaded zipper tapes which consists in forming a bead along a longitudinally extending edge of a flat tape fabric preliminarily to dyeing the same, in then dyeing the beaded tape, and in thereafter pressing the beaded zipper tape into final condition by simultaneously subjecting the flat body portion thereof to the pressing action of a pair of opposed flat heated surfaces and the beaded portion thereof to the pressing and shaping action of a pair of opposed complementally grooved heated surfaces.

2. A method of manufacturing beaded zipper tapes which consists in forming a bead along a longitudinally extending edge of a flat tape fabric preliminarily to dyeing the same, in then dyeing the beaded tape, and in thereafter pressing the beaded zipper tape into final condition by subjecting the flat body portion thereof to the pressing action of a pair of opposed heated surfaces with the beaded edge of the tape non-crushingly disposed during the pressing action between said tape-pressing surfaces.

3. A method of manufacturing beaded zipper tapes which consists in forming a bead along a longitudinally extending edge of a flat tape fabric preliminarily to dyeing the same, in then dyeing the beaded tape, and in thereafter pressing the beaded zipper tape into final condition by

subjecting the flat body portion thereof to the pressing action of a pair of opposed heated surfaces while maintaining the beaded edge of the tape snugly accommodated during the pressing action within a recess formed between said tape-
pressing surfaces to shape said beaded edge longitudinally of its length to a substantially uniform cross-section.
